US00D721359S

(12) **United States Design Patent**
Kim

(10) **Patent No.:** **US D721,359 S**
(45) **Date of Patent:** **** Jan. 20, 2015**

(54) **CASE FOR A PORTABLE TERMINAL**

(71) Applicant: **Soong Jae Kim**, Seoul (KR)

(72) Inventor: **Soong Jae Kim**, Seoul (KR)

(73) Assignee: **Soong Jae Kim**, Seoul (KR)

(**) Term: **14 Years**

(21) Appl. No.: **29/488,984**

(22) Filed: **Apr. 25, 2014**

(30) **Foreign Application Priority Data**

Oct. 25, 2013 (KR) 30-2013-0053872

(57) **CLAIM**

The ornamental design for a case for a portable terminal, as shown and described.

DESCRIPTION

FIG. 1 is a front perspective view of the case for a portable terminal showing my new design in a first configuration; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is a perspective view of the case for a portable terminal showing my new design in a second configuration; FIG. 9 is a front elevational view thereof; FIG. 10 is a rear elevational view thereof; FIG. 11 is a left side elevational view thereof; FIG. 12 is a right side elevational view thereof; FIG. 13 is a top plan view thereof; FIG. 14 is a bottom plan view thereof; and, FIG. 15 is a perspective view thereof showing the case for a portable terminal in a state of use with an unclaimed portable terminal.

In FIG. 15, the unshaded front surface and the broken lines thereon depict an unclaimed portable terminal.

1 Claim, 14 Drawing Sheets
